UNITED STATES PATENT OFFICE.

RUFUS M. BRUNDIGE, OF NEW YORK, N. Y.

DESIGN FOR A DISH.

SPECIFICATION forming part of Design No. 12,422, dated August 16, 1881.

Application filed June 21, 1881. Term of patent 14 years.

To all whom it may concern:

Be it known that I, RUFUS M. BRUNDIGE, of the city, county, and State of New York, have invented a new and original Design for 5 Dishes, of which the following is a specification, reference being had to the accompanying drawings, forming part thereof.

Figure 1 is a perspective view of a sugar-bowl illustrating my design. Fig. 2 is a perspective view of a pitcher illustrating my design. Fig. 3 is a sectional plan view taken through the line $x x$, Fig. 1. Fig. 4 is a plan view of a cover for the dish shown in Fig. 1.

Similar letters of reference indicate corresponding parts.

The object of this design is to give an ornamental configuration to covered and uncovered dishes, such as vegetable-dishes, sugar-bowls, tea-cups, pitchers, and other dishes of 20 a table-service with handles.

The design consists in making a dish rhomboidal or diamond shaped, with the acute angles cut off, forming four wide and two narrow sides, and provided with handles at the 25 cut-off acute angles rising obliquely above the dish, as will be hereinafter fully described.

A represents the bottom of the dishes, and B the sides, which incline or flare outward from the said bottoms A. The bottoms A are made 30 rhomboidal or diamond shaped, with the acute angles cut off, as shown in Fig. 3. The bodies of the dishes are made in corresponding form. The dishes may be provided with handles C C' and with spouts D. The handles C of the 35 dishes, except the tea-pots, pitchers, and cups, rise obliquely above the said dishes at the cut-

off acute angles, as shown in Fig. 1. The handles C' of the tea-pots, pitchers, and cups are made angular, as shown in Fig. 2. The covers are also made rhomboidal or diamond shaped, with the acute angles cut off, forming four wide sides, E, and two narrow sides, E', the sides of the said covers rising obliquely to the top, which is made flat, and is provided with a flat vertical handle, F, to correspond 40 with the shape of the dishes to which they are to be applied. This configuration makes the dishes six-sided—two wide sides, B, at each side, and a narrow side, B', at each end, as shown in the drawings.

Having thus fully described my invention, I claim as new and desire to secure by Letters Patent—

1. The design for dishes, as herein shown and described, which consists of a dish having a rhomboidal or diamond shape, with the acute angles cut off, forming four wide and two narrow sides, and provided with handles at the cut-off acute angles rising obliquely 55 above the dishes, as set forth.

2. The design for dish-covers, as herein shown and described, which consists of a cover having a rhomboidal or diamond shape, with the acute angles cut off, forming four wide and two narrow sides, with the sides rising obliquely, and with a flat rhomboidal top provided with a vertical handle, as set forth.

RUFUS M. BRUNDIGE.
